FRANCIS S. FARLEY, OF TRENTON, NEW JERSEY

SHEET-HANDLING AND TRANSFER MECHANISM

Application filed September 24, 1928. Serial No. 307,822.

My invention relates to sheet handling and transfer, and is especially adaptable and advantageous for dealing with sheets of wet fibre pulp in the manufacture of fibre board.

In such manufacture, fibre pulp is brought into sheet form (and freed of much of its water) in an apparatus known as a "wet machine". The resulting sheet of wet, ¹⁰ loosely coherent pulp is transferred to an apparatus known as a "drier", where it is compacted into a strong, coherent board by heat and pressure, and dried out by the heat.

¹⁵ In transferring the wet pulp sheet from the wet machine to the drier, I prefer to make use of an apparatus which I call a "loader", more fully described in the application of D. Manson Sutherland (assignee of this application), Serial No. 307,839 filed concurrently with this application. Such a loader comprises a horizontal reciprocating carriage, which picks up the sheet and introduces it between the heated plates of ²⁰ the drier. To enable the loader to pick up a sheet lying flat, the latter (or at least its margin or edge) must be lifted in front of the loader, to allow the latter to enter beneath it.

²⁵ My present invention is applicable and very useful for this purpose; and I have hereinafter described and explained it as thus applied.

In the drawings, Fig. I is a side elevation of a loader with my present invention applied in connection therewith.

Fig. II is a fragmentary view similar to Fig. I, but showing the loader just entering beneath the lifted margin of a sheet,—with certain parts broken away and in vertical section.

Fig. III is an elevation of the lifter, from the right of Fig. I.

⁴⁵ Fig. IV shows a cross-section through a suction-controlling valve.

Fig. V shows a cross-section through a suction element forming part of the lifting device, taken as indicated by the line V—V in Fig. VII.

Fig. VI is an end or side elevation of the suction element, from the left of Fig. V.

Fig. VII is a top plan view of the suction element; and,

Fig. VIII a bottom plan view.

As shown in Fig. I, the transfer mechanism or loader comprises a carriage 10 that travels back and forth along horizontal ways or rails 11 carried by suitable uprights 12, such as the pillars or posts of the building in which the apparatus is housed. As shown, the carriage 10 has supporting wheels or rollers 13 for the rails 11, and also underrunning rollers 14 mounted on brackets 15 at the rear end of the carriage and engaged underneath the top flanges of the rails 11,—which are of I section. The rollers 14 serve to prevent the free end of the carriage 10 from tipping down. For supporting the fibre sheet, the carriage 10 has a movable apron 16, preferably pervious or foraminous, in the form of a belt running around rolls 17, 17 at either end of the carriage 10. There is also a short belt 18 just in front of the belt 16, running around small rolls 19. These rolls 19 are so small that the front one can easily enter beneath the margin of a lifted sheet,—which the belt 18 will then feed along to the main belt 16. A reversible (electric) motor 20 on the carriage 10 acts through suitable connections to drive the carriage to and fro on the rails 11, and also drives the belts 16, 18 both ways relative to the carriage. Wet fibre sheets S are shown in a pile 21 in front of the carriage 10, on a truck 22 on rails 23 on an elevator 24,—

which may serve to bring them from a wet machine located at a different level (not shown), as well as to adjust the top of the pile to the proper height as sheets are removed from it. The drier (not shown) into which the sheets are successively introduced by the carriage 10 is located off the paper to the right, at the other side of the pile 21 from the carriage as shown in Fig. I.

In operation, the unloaded carriage 10 recedes (toward the left) over the pile 21, after introducing a sheet S into the drier, to the position shown in Fig. I. The carriage 10 then returns forward toward the

100

pile 21 and enters beneath the front edge or margin of the top sheet S,—which has meantime been lifted or turned up (as shown in Fig. II and described hereinafter) to admit the front edge of the carriage, consisting of the belt 18. During this return movement of the carriage 10 (toward the right), the upper runs of the belts 16 and 18 travel in the opposite direction (toward the left) relative to the carriage, at a linear speed equal to the rate of travel of the carriage; and thus the sheet S is progressively lifted and picked up on the carriage in situ, without being moved horizontally relative to the pile 21, and without risk of breakage. The rearward movement of the belts 16 and 18 relative to the carriage 10 now ceases, and the carriage moves on forward over the pile 21 into the drier (not shown), carrying the sheet S bodily with it between the plates of the drier. The carriage 10 then recedes (toward the left) while the belts 16 and 18 travel in the opposite direction (toward the right) at a rate of speed equal to the rate of travel of the carriage; and thus the sheet S is dropped or deposited in situ in the drier (by a simple reversal of the operation of picking it up), without being moved horizontally relative to the drier. The carriage 10 continues its movement to the left over and beyond the pile 21 to its position shown in Fig. I,—as already described.

For lifting the margin of the top sheet S in front of the advancing carriage 10, as mentioned above, there is a transverse lifter 30 (Fig. I) which is automatically raised and lowered in definite correlation with the movement of the carriage, and preferably by the latter itself. As shown in Fig. I, this is done by means of one or more hoisting cables 31 extending from the lifter 30 up over sheaves 32, and thence rearward under sheaves 33, with ultimate connection to the rear of the carriage 10 at 34. The lifter 30 is preferably guided or restrained in its up and down movement by guide means 35, shown as consisting of vertical channels at either end of the lifter, and the lifter may have round heads or anti-friction rollers 36 to engage in the channels 35. As indicated by Figs. I—III the channels 35 are wide enough to allow the lifter some range of self-adjustment or play. To avoid an excessive range of movement of the lifter 30, the cables 31 are not connected directly to the carriage 10, but reductively geared thereto, the gear shown consisting of a two-block tackle. The cable 37 of this tackle is attached to the fixed block 38 mounted on the beam 39. The movable block 40 is supported by an overhead guide 41, through anti-friction rollers 42 running on the guideways. The cables 31 are attached to the ends of a spreader 43 to the middle of which the movable block 40 is connected,

From the movable block 40, the cable 37 extends rearward over a pulley-sheave 44 mounted on the beam 39, and down and around a pulley-sheave 45 mounted at the rear ends of the carriage ways 11.

The lifter 30 preferably holds on to the sheet S by suction. Accordingly, it is connected by flexible connections 46, 47 to a suction line 48 leading to any suitable exhauster or the like. As a means of releasing the sheet S after the carriage edge at 19 has entered beneath it, provision may be made for cutting off the lifter connections 47 from the suction line 48, and opening said connections 47 to the atmosphere. As shown, one or more rotary plug valves 50 are provided for this purpose, being located adjacent the hoisting cable 31 so that the valve may be actuated by a ball 51 or the like suitably fixed on the cable. As shown in Fig. I, the rotary body of the valve 50 has oppositely bent arms or horns 52, 52 for the ball 51 to engage and act on,—the ball pushing each horn 52 to the limit of its movement in each direction, and then slipping under its curved tip, or even past it. As shown in Fig. I, the lifter 30 has settled down fully on the top sheet S, the carriage 10 is in its extreme rear position, the ball 51 is at the limit of its movement, and the valve 50 is full open to connect the lifter 30 to suction. The valve 50 is closed to suction and opened to the atmosphere where the margin of the sheet has been lifted somewhat higher than required to admit the carriage edge beneath it, as shown in Fig. II.

As here shown, and especially in Figs. I—III and V, the lifter 30 comprises a transverse header 53 with duplicate suction connections 47, 47 leading to the valve 50, and multiple connections 46 to its multiple suction mouths or chambers. On the header 53 are clamped a couple of triangular parts 54 to which the duplicate hoisting cables 31 are attached at 55, and which carry pivots 56 for suspension links 57, 58 connected to slotted ears 61, 62 on the lifter 30 proper by pivot rods 63, 64. The slots in the ears 61, 62 afford some lost motion or leeway for descent of the parts 53, 54, etc. after the lifter 30 has settled down on a sheet S,—in other words, leave the lifter 30 freedom of self-adjustment to the sheet uninfluenced by the parts 53, 54, etc. and the hoisting cable 31,—and also allow the valve 50 to be operated after the lifter has settled down on the sheet S. As shown in Figs. I, II and V, the effective connections of the hoisting means 31, 54 to the lifter 30 at the pivots 56 are in front of the center of gravity of the lifter, so that as the cable 31 is taken up, the lifter will tilt rearward away from the edge of the sheet, as shown in Fig. I, and thus tend to bend up the

margin of the sheet around the rear corner of the lifter. Accordingly, the lifter has a rearward extension or curved lip 66 on which it rocks when thus tilted, so as to assure an easy bend in the sheet. Preferably, the lower ends of the rear links 58 are slotted as at 68, so that the lifter 30 will be tilted and rocked as shown in Fig. II before there can be any tendency to raise the lifter as a whole.

As shown in Figs. III and V-VIII, the suction mouths and chambers of the lifter 30 are in separate and independent units 70, each with its own ears 61, 62 and flexible suction connection 46. This allows the suction mouths to settle down and adjust themselves individually to the surface of the sheet, so as to minimize leakage and give the lifter the greatest possible lifting power. The pivot rods 63, 64 transmit the weight of the sections to the connections 57, 58, 54 and the cables 31, forming what is in effect a somewhat resilient, flexible transverse lifting yoke. Each lifter unit 70 may have a cast metal body and a contact facing 71 of softer and more yielding material, such as rubber. As shown, the facing 71 has the form of a frame with a protective grid work 72. In addition, there is a foraminous guard 73 over the mouth, shown in the drawings as a metal plate drilled with a multitude of fine holes closely spaced. The plate 73 seats in a rabbet in the facing 71, and is held in place by screws 74 that extend through the facing 71 into the body 70, thus securing the facing to the body. The lip portion 75 of the facing 71 is secured to the lip 66 of the body by bolts 76 through its margins, a bevel-edged metal strip 77 being interposed to afford a better hold for the bolt heads.

As will be seen from Figs. V and VI, the edges of the rubber facing 71 flare outward, so as to yield to the external atmospheric pressure when vacuum is "on" the lifter 30, and so hug the surface of the sheet and its inequalities. The grid or grillage 72 prevents the sheet from being drawn up into the suction mouth excessively and ruptured by the suction. Being of rubber, this grillage 72 yields laterally to the degree allowed by the plate 73, and also yields to permit some inward deflection of the facing 71 by the atmosphere.

Having thus described my invention I claim:

1. The combination of a reciprocatory self-feeding sheet-transfer carriage, a lifter for engaging a sheet in front of the carriage, and means for lowering the lifter on the margin of a sheet as the carriage recedes therefrom and raising the lifter as the carriage returns, thereby lifting said margin to admit the edge of the carriage thereunder, so that the self-feeding carriage may draw

the sheet on to itself as it returns toward and under the sheet.

2. The combination of a reciprocatory self-feeding sheet-transfer carriage, and a lifter for engaging a sheet in front of the carriage reductively geared thereto to be lowered on the sheet as the carriage recedes therefrom and to be lifted with the margin of the sheet as the carriage returns.

3. The combination of a reciprocatory self-feeding sheet-transfer carriage, a lifter for engaging a sheet in front of the carriage, and means for raising and lowering said lifter including a cable connected to the carriage to be paid out as the latter recedes from the sheet and pulled up as the carriage returns.

4. The combination of a reciprocatory sheet-transfer carriage, a transverse lifter for engaging a sheet in front of the carriage, means for raising and lowering the lifter including a hoisting cable connected to the lifter and operated by the carriage, and upright guideways for the ends of the lifter at either side of the path of the carriage.

5. The combination of a reciprocatory sheet-transfer carriage, a lifter for engaging the margin of a sheet in front of the carriage, and hoisting and lowering means operated by the carriage and attached to the lifter in front of its center of gravity, so that as the lifter rises it shall rock inward from the edge of the sheet and turn up the margin of the latter.

6. The combination of a reciprocatory sheet-transfer carriage, a lifter for engaging the margin of a sheet in front of the carriage and raising the same to admit the edge of the carriage thereunder, a lifting and lowering cable for said sheet lifter, and a reductive tackle connected to said cable and operated by said carriage to lower the lifter on a sheet as the carriage recedes therefrom and to raise the lifter and the margin of the sheet as the carriage returns.

7. The combination of a reciprocatory sheet-transfer carriage, a suction lifter for engaging a sheet in front of the carriage provided with a lip curved rearward and upward from the suction mouth, and hoisting means operated by the carriage and connected to said lifter in front of its center of gravity, so as to rock the lifter rearward on its lip in raising it and thus turn up the margin of the sheet in an easy bend.

8. The combination of a reciprocatory sheet-transfer carriage; a suction lifter for engaging the margin of a sheet in front of the carriage; means for lowering the lifter on a sheet as the carriage recedes from the sheet, and raising the lifter as the carriage returns; and means for automatically connecting the lifter to suction when it descends on the sheet and disconnecting it

from suction as the carriage enters beneath the sheet.

9. The combination of a reciprocatory sheet-transfer carriage; a suction lifter for engaging the margin of a sheet in front of the carriage; a lifting and lowering cable for said lifter with reduction gearing interposed between the same and the carriage; and means actuated by said cable for connecting the lifter to suction when it descends on the sheet and disconnecting it from suction as the carriage enters beneath the raised margin of the sheet.

10. The combination of a reciprocatory sheet-transfer carriage; a suction lifter for engaging the margin of a sheet in front of the carriage; means for lowering the lifter on a sheet, and rocking it away from the edge of the sheet so as to turn up the margin, as the carriage recedes from the sheet, and raising the lifter as the carriage returns; and means for automatically connecting the lifter to suction when it has settled down on the sheet and disconnecting it therefrom after the carriage has entered beneath the turned up margin of the sheet.

11. The combination of a reciprocatory sheet-transfer carriage, a suction lifter for engaging a sheet in front of the carriage, control means for connecting the lifter to suction and disconnecting it therefrom, and hoisting means for said lifter provided with means for actuating said control means and including a lost motion between the latter and the lifter, so that the lifter may settle down on the sheet before being connected to suction.

12. The combination of a reciprocatory sheet-transfer carriage, and a suction lifter for engaging a sheet in front of the carriage comprising a resilient flexible transverse lifting yoke operated by the carriage and a series of suction elements with separate lost-motion connections to the yoke, so that the elements may adjust themselves individually to the surface of the sheet.

13. The combination of a reciprocatory sheet-transfer carriage, and a suction lifter for engaging a sheet in front of the carriage comprising a transverse lifting yoke operated by the carriage and a series of suction elements with supporting connections arranged to allow the elements to adjust themselves to the sheet individually when they are lowered on it and to tilt back away from the carriage when they are lifted.

14. The combination of a reciprocatory sheet-transfer carriage, and a suction lifter for engaging a sheet in front of the carriage having a suction mouth with flaring edges yielding to external atmospheric pressure so as to hug the sheet, and means across the mouth for preventing a sheet from being drawn into it by the suction.

In testimony whereof, I have hereunto signed my name at Trenton, New Jersey, this 18th day of September, 1928.

FRANCIS S. FARLEY.
